METHOD OF MAKING A GOLF BALL

Augustus W. Crane, Kalamazoo, Mich.; C. Hubbard Kleinstuck, executor of the estate of said Augustus W. Crane, deceased

Application August 8, 1935, Serial No. 35,356

11 Claims. (Cl. 154—18)

The main objects of this invention are:

First, to provide golf balls which have a high degree of internal pressure and a highly elastic core.

Second, to provide a method of producing golf ball cores containing a gas developed within the core.

Third, to provide a method of producing highly tensioned golf balls.

Fourth, to provide an improved golf ball which is well balanced and capable of long and accurate flight.

Fifth, to provide a method of manufacturing golf balls having the above stated qualities.

Objects pertaining to details and economies of my invention will definitely appear from the description to follow. The invention is defined in the claims.

A golf ball embodying the features of my invention is clearly illustrated in the accompanying drawing, in which:

Fig. 1 is a side elevation of a golf ball embodying my invention.

Fig. 2 is a central section on line 2—2 of Fig. 1 of a finished golf ball.

Fig. 3 is a section through the hollow core.

Fig. 4 is a section through a filled core prior to the development of the gas therein.

Fig. 5 is a section through a wound core prior to the development of the gas therein.

Fig. 6 is an elevation of the core, the expansion thereof being indicated by the concentric dotted lines.

Referring to the drawing, the numeral 1 indicates a golf ball generally, which comprises a core 2, a body 3 and a shell 4. The core is a hollow elastic shell containing an expansion medium indicated at 5. The body 3 is formed by winding upon the core ribbon or elastic strands under stretching tension. This method of winding may be that commonly employed in the manufacture of golf balls.

I provide a high elastic tension within the core by introducing therein, before winding, a material suitable for the growth of gas-forming micro-organisms, the material having been inoculated, previous to being introduced into the core, with the selected organisms. The gas-forming micro-organisms include molds, yeasts and bacteria. The material or culture medium suitable for the growth of any one of these organisms may be of various compositions containing carbo-hydrates, proteids, or hydrocarbons. The culture medium is of such a composition that the formed gas will remain evenly distributed throughout either

in a jelly paste or by means of a matrix such as sponge rubber, so that the center of gravity of the ball will remain unchanged. The degree of tension may be regulated by maintaining the control of temperature for a predetermined time and then sterilizing as by pasteurization, or by using a measured quantity of fermentable material. The culture may be allowed to die from products of its own metabolism in a balance culture medium.

By this method a very substantial pressure within the core may be produced, depending upon the type of organism, the culture medium, and the length of time permitted for development thereof.

Inasmuch as the cores, filled with inoculated material, may be wound completely before gas formation is permitted, it is possible to produce golf balls by my method having very high pressures within the cores, because the windings about the cores provide ample resistance to expansion and rupture, this allowing a degree of gas compression not otherwise possible. Since the degree of gas compression within the core of a golf ball becomes an important factor in the elastic tension of the ball as a whole, this factor determines the distance over which a golf ball can be driven.

The growth of certain micro-organisms and thus the production of gas within the cores is controllable by temperature but golf balls may be manufactured by this method under favorable factory conditions; for example, the winding operations can be performed at more comfortable temperatures than are practical with certain methods of manufacturing golf balls now practiced. Further, the pressure within the ball can be very accurately controlled and the center of gravity is maintained throughout the life of the ball, depending on the nature of the core filling medium.

It will be understood that no effort has been made to show the elements of the ball in proportion, the drawing being by way of illustration only.

I have not attempted to point out all the modifications which might prove practical as it is believed that this disclosure will enable those skilled in the art to practice my invention as may be desired.

Having thus described my invention what I claim as new and desire to secure by Letters Patent is:

1. The method of forming golf balls consisting of introducing into a spherical flexible shell a

- material suitable for the growth of gas-forming micro-organisms inoculated with the organisms, and winding the core with elastic strands under tension prior to such growth of the gas-forming 5 micro-organisms so that the development thereof will result in a core under high elastic tension.
2. The method of making golf balls consisting of introducing into a hollow elastic spherical core a measured quantity of fermentable material, 10 and winding with elastic strands under tension prior to the expansion of the core by the fermentation of the material therein so that the expansion of the material within the core results in producing internal tension.
- 15 3. The method of forming golf balls consisting of introducing into a hollow expandible core a micro-organism inoculated culture medium, winding, maintaining the wound ball for a pre-determined time at a temperature suitable for 20 the growth of the micro-organisms within the wound core to expand the core within the winding and develop an internal pressure, and then sterilizing by pasteurization to stop the growth.
4. The method of forming golf balls consisting 25 of introducing into a hollow expandible core a micro-organism inoculated culture medium, winding, and permitting the growth of the micro-organisms within the wound core to expand the core within the winding and develop an internal pressure.
- 30 5. The method of forming golf balls consisting of the step of introducing into a hollow expandible core a micro-organism inoculated culture medium, maintaining the wound ball for a period 35 and temperature suitable for the growth of the micro-organisms within the core, and then sterilizing.
6. The method of forming golf balls consisting 40 of the step of introducing into a hollow expandible core a micro-organism inoculated culture medium, and permitting the development of the

micro-organism within the core to produce expanding pressure therein.

7. The method of forming golf balls consisting of introducing into a spherical flexible core shell a material suitable for the growth of a gas-forming micro-organism inoculated with the organism, and winding the core with elastic strands under tension prior to such growth of the gas-forming micro-organisms. 5

8. The method of making golf balls consisting 10 of introducing into a hollow elastic spherical core a measured quantity of inoculated micro-organism culture material, and winding with elastic strands under tension prior to the expansion of the core by the material therein so that the expansion of the material within the core results 15 in producing a high tension ball.

9. The method of making golf balls consisting of the step of introducing into a hollow elastic spherical core a measured quantity of inoculated 20 micro-organism culture material, and permitting the development of the micro-organisms within the core. 25

10. In a method of forming golf balls, the steps of introducing into a hollow expandible core a 30 micro-organism incculated with a culture medium and a sponge-rubber matrix therefor, winding the core, permitting the micro-organism to develop, and terminating the development by sterilization when the pressure of the gas produced by the development reaches a predetermined value. 35

11. In a method of forming golf balls, the steps of introducing into a hollow expandible core a 40 micro-organism inoculated with a culture medium and a matrix therefor, permitting the micro-organism to develop, and terminating the development when the pressure of the gas produced by the development reaches a predetermined value. 45
